MEASURED-VOLUME DISPENSER FOR CHEMICAL REAGENTS OR THE LIKE

John J. Moran and Robert C. Querry, Houston, Tex., assignors to Hycel, Inc., Houston, Tex.

Filed Jan. 5, 1970, Ser. No. 20,759

Term of patent 14 years

Int. Cl. D24—02

U.S. Cl. D16—1

FIG. 1 is a front view of a measured-volume dispenser for chemical reagents or the like, showing our new design;

FIG. 2 is a side elevation thereof; and

FIG. 3 is a top view thereof.

We claim:

The ornamental design for a measured-volume dispenser for chemical reagents or the like, as shown.
